UNITED STATES PATENT OFFICE.

EMERSON L. CLARK, OF LAKEWOOD, OHIO, ASSIGNOR, BY MESNE ASSIGNMENTS, TO
NATIONAL CARBON COMPANY, INC., A CORPORATION OF NEW YORK.

BRUSH-HOLDER.

1,293,038.

Specification of Letters Patent.

Patented Feb. 4, 1919.

Application filed April 19, 1916. Serial No. 92,152.

To all whom it may concern:

Be it known that I, EMERSON L. CLARK, a citizen of the United States, residing at Lakewood, in the county of Cuyahoga and State of Ohio, have invented a certain new and useful Improvement in Brush-Holders, of which the following is a full, clear, and exact description.

This invention relates to brush holders for dynamo electric machines. In brush holders at present in use the brush is supported at points a considerable distance above the commutator surface, and as the commutator rotates the brush is carried forward at the bottom in the direction of rotation and the top is tipped backward. Consequently the brush is not held firmly against the commutator, but makes small but appreciable vibrations which vary the contact resistance and cause undue friction and heating of the commutator. In all such types of brush holders the resultant force resisting the effort of the commutator to drag the brush along with it, is through the center of the holder which may be an inch or more above the surface of the commutator. Since the turning force exerted on the brush by the commutator is in the circumference of the commutator, there is always a considerable moment of rotation tending to tip the brush around, thus destroying the fit of the brush on the commutator.

My invention overcomes the above difficulties and consists of an arrangement whereby the resultant reacting force is exerted in the same plane as the turning force due to friction on the commutator, namely in a plane tangent to the commutator at the center of the brush.

Referring to the drawings:

Figure 1 is a top view of a brush holder and commutator embodying my invention.

Fig. 2 is an end view of the brush holder and commutator.

Fig. 3 is a perspective view of the brush clamp.

Fig. 4 is a front view of the brush holder prongs.

Fig. 5 is a view of a modified form.

Fig. 6 is a perspective view of the clamp used in the modification of Fig. 5.

Fig. 7 is a modified form of brush clamp.

To carry out my invention, I affix a clamp 1 around the brush 2 so that the brush can-

not slide therethrough. In the drawing I have shown a rectangular member having a clamping screw 3, so that the brush can be loosened at intervals and pushed farther through the clamp when it is worn down sufficiently to make this necessary. When the adjustment is made the brush will be reclamped by tightening the screw.

The clamp 1 has projections 4 adapted to engage projections 6 which are integral with or otherwise secured to prongs 7 on the holder arms 8.

The invention can be used with one or any number of brushes, but I have illustrated it in connection with two brushes, and in such an arrangement it is convenient to have one brush holder for the two brushes. This makes it desirable to have three of the prongs 7 on the holder and two holder arms 8, although this may be varied without departing from the spirit of the invention.

The holder arms 8 may be secured to the brush rocker arm 9 by a rod 10 passing through holes 11 in the arms. Set screws 12 bind the brush holder in any position on the rod 10 so that it can be adjusted to the desired height above the commutator 13. The brushes are yieldingly forced against the commutator by any means, shown by way of example as springs 14 having one end coiled around the shaft 10 and secured thereto by screws 15, while the other end rests on the center point of the frame, as clearly shown in Fig. 2. In order to insure that the springs exert their force at the center of the brush, it is preferable to bend the ends into an arc as shown at 16.

As indicated in Fig. 1, there is a spring 14 bearing on top of the clamp 1 at each side of the brush. As previously stated, the springs may be of any form and they may have various means for adjusting their tension, but in the more or less diagrammatic form illustrated on the drawing, the adjustment would be made by loosening a set screw 17 in the rocker arm and turning the rod 10 until sufficient tension is obtained. On screwing down the set screw this tension will be maintained.

The operation of my improved form of brush holder will now be described. The holder arm will be adjusted toward the commutator so that the center plane of the projections 6 is tangent to the surface of the

commutator, and in order to permit this the commutator has been previously grooved at 18 sufficiently to give proper clearance. When the holder arms have been adjusted 5 to the position referred to, they are clamped rigidly to the rod 10 by set screws 12. The brush is then placed in position with the projections 4 abutting against the projections 6 on the holder prongs, as clearly 10 shown in Figs. 1 and 2. The ends of the springs 14 are next placed on the brush clamp to force the brush radially onto the commutator. With this position of the brush holder, the reactive force of the brush, 15 indicated by arrow 19, is exactly in the same line as the turning force of the commutator, indicated by arrow 20. Consequently there will be no vibration, no chattering and no tilting of the brush during the operation of 20 the motor.

In Fig. 5 a modification is shown with the projections 4 extending downward from the bottom edge of the brush clamp 1, instead of along the outside. This permits 25 of the use of a smaller slot in the commutator and also enables the brushes to be placed closer together. There consequently will be less waste surface of the commutator.

When my improvement is to be used on 30 dynamo electric machines that are reversible in operation, I may make two projections on the clamp 1, as shown in Fig. 7. The projection on the holder arm would therefore exert a reactive force on the brush in 35 either direction of rotation. This is only approximately correct in principle, as the two edges 5 of the projections are not in the central plane of the brush. However, the results obtained will be much better than 40 with types already in use.

It is preferable to take the current off the brush by pigtails 21 which may be secured to the brush and brush holder in any well known manner.

Copies of this patent may be obtained for five cents each, by addressing the "Commissioner of Patents, Washington, D. C."

In case brushes are used that have a height 45 not much greater than their thickness, one spring only may be used, and this may bear against the center of the top of the brush.

Having described my invention, what I claim is:—

1. In dynamo electric machines, a movable conductor, means for collecting current from the surface of said conductor, a stationary holder engaging said means at points substantially in a plane tangential to the 55 conductor at the center of the said collecting means.

2. In dynamo electric machines, a movable conductor, means for collecting current from the surface of said conductor, projections at the center of the sides of said means substantially in a plane tangential to the 60 conductor, a stationary holder engaging said projections, and a spring exerting pressure to force said means against the 65 conductor.

3. In dynamo electric machines, a movable conductor, a brush, a clamp around said brush having two members adapted to lie substantially in a plane tangential to the 70 conductor at the center of the brush, a spring to force the brush against the conductor, and a brush holder engaging said members.

4. In dynamo electric machines, a cylindrical commutator, a brush adapted to contact therewith, a clamp secured to said brush and having two members projecting at the sides below the current collecting surface of said commutator, and a holder engaging said projections substantially in the plane 75 of the current collecting surface of the commutator at the center of the brush, said conductor being circumferentially grooved to provide clearance for said projections.

In testimony whereof, I hereunto affix my 85 signature.

EMERSON L. CLARK.
